UNITED STATES PATENT OFFICE.

MILTON L. DODGE, OF NEWBURYPORT, MASSACHUSETTS.

METHOD OF MAKING TURN SHOES.

Application filed February 20, 1924. Serial No. 694,130.

- This invention relates to methods of making turn shoes by which the work may be much expedited and by which the number of lasts necessary to produce a given output is 5 very much reduced over methods heretofore used. For certain grades of shoes also it is possible with the methods of the present invention to eliminate the necessity of relasting the shoes after the turning operation.
- 10 For a more complete understanding of this invention reference may be had to the accompanying drawings in which Figure 1 is an elevation partly broken away showing a shoe including a tempered toe 15 stiffener lasted wrong side out.
- Figure 2 shows the shoe after it has been removed from the last and turned and in place in a molding press for molding the entire shank and forepart of the sole to form.
- 20 Figure 3 is an elevation partly in section showing the toe portion of the shoe drawn over a heated form to smooth the lining and set the toe stiffener.
- Figure 4 shows the heel portion of the shoe 25 with a counter stiffener in position and drawn on a heated form to smooth and shape the heel portion.
- Figure 5 shows an elevation of the shoe prepared for the finishing operations.
- 30 Figure 6 is an elevation of the shoe as lasted wrong side out and without a toe stiffener.
- Figure 7 is a fragmentary plan of the toe portion of the same showing the manner in which the lining may be stitched to facilitate 35 the subsequent positioning of a previously molded toe stiffener.
- Figure 8 shows the last drawn, the shoe turned and the forepart and shank of the sole being molded to form.
- 40 Figure 9 shows the shoe after removal from the press and with the toe stiffener in place ready to be shaped on the heated forms as shown in Figures 3 and 4.
- When it is desired to use a previously 45 tempered box toe sewed into the shoe upper before the shoe is assembled the method shown in Figures 1 to 5 may be employed. Referring to Figure 1, 1 indicates the last on which the shoe is assembled, 2 the sole, 3 the upper, 50 4 the doubler, and 5 the vamp lining. Between the doubler 4 and the lining is positioned the toe stiffener 6 which in this construction is usually formed of fabric treated with a suitable compound which may be 55 treated with a liquid so as to become soft and "tempered" and which becomes hard when
- dry. At 7 is indicated the counter lining and at 8 the inseam. The inseam is trimmed and preferably the forepart of the sole is pressed so as to flatten the inseam and close up the channel in the sole.
- The last having been withdrawn and the shoe turned, the bottom of the sole is then molded to form between molding blocks 10 and 11 as shown in Figure 2. The shoe is 60 then removed from the molding forms and the toe portion is drawn over a form shown at 15 in Figure 3 which may be heated to expedite the drying of the stiffener if desired. This form is shaped to the contour of the last and acts to shape the box toe and if heated dries out and sets the box toe and at the same time the upper at the toe may be smoothed down to proper form. If the shoe is allowed to dry out on a last to set the toe stiffener, 65 several days may be required for it is impossible for the air to get to the shoe on the inside and the wooden last helps to retain the moisture. With the present method the shoe is removed from the form and air is 70 permitted to reach the inside of the shoe so that the drying operation is rapidly effected. Where the form is heated it is so conditioned that the drying is further expedited. If desired the toe may be drawn on to the form 75 before the bottom of the shoe is molded. The shoe is laid aside without the last therein and the sole and upper permitted to dry out thoroughly, which ordinarily may be done within a few hours. After the drying the shoes 80 may progress through the factory in case lots since they are no longer in temper. A counter 85 shank piece 14 may then be assembled in the heel portion of the shoe and the lining tucked inside the counter in proper shape. If desired also, a counter stiffener softened by treatment with a liquid might be used and shaped and set as above described with relation to the toe stiffener.
- When a comparatively cheap grade of shoes 90 is being made where the upper leather is rather heavy, the heel portion of the shoe may be properly smoothed and shaped by drawing it onto a heated metal heel form as shown at 16 in Figure 4, this form being 95 complementary to the form 15 of Figure 3, both together being in the shape of a last. These forms may be heated in any suitable way, but a convenient means of accomplishing this is by means of the electric heating elements 17 and 18 inserted in suitable openings in the 100 forms. Where comparatively cheap shoes

are being made the smoothing of the heel and toe portions over the forms is sufficient to finish the upper and shape the shoe without the necessity of any relasting operation, the 5 shoes progressing, also, if desired, through the various operations of heelng and finishing while off lasts. When this is done it is preferable to hold the shoes against buckling or being bent in handling by means of spreaders such as strips of rattan or other resilient material 19 (Figure 5) engaging at opposite ends in the inner faces of the toe and counter and of sufficient length to be sprung into position. Where a more expensive grade of 15 shoes is being made the shoe may be relasted after the counter is in position and finished in the usual manner. With either method, however, the drying out of the sole and the setting of the toe stiffener is performed while 20 the shoes are off the lasts so that the large number of lasts heretofore necessary to carry the shoes during the several days in which drying takes place are entirely unnecessary. 25 Where the cheaper grades of shoes are being made it is unnecessary to employ any lasts after the shoes have been turned.

In case it is desired to use a previously molded toe stiffener, the method may be carried out as follows. It is preferable where 30 molded toe stiffeners are used to stitch the opposite edges of the lining together adjacent the toe for a short distance as shown at 20 in Figures 6 and 7. The upper with the lining stitched in this manner is then assembled on 35 the last as shown in Figure 6, the lining being unstitched to the sole for a portion of its length from the toe end. The shoe is stitched on the last and the seam flattened, particularly at the toe end where the stiffener is to engage, so that a proper surface will be presented for it to engage upon and which will permit it to be placed in position readily. 40 After the shoe is thus assembled the last is withdrawn and the shoe turned and the sole is molded as between the forms 10 and 11 in the same manner as illustrated in Figure 2. The shoe having been removed from the molding form, the box toe is inserted in position and the lining is tucked within it, as shown in 45 Figure 9, the stitching 20 causing the lining at the toe to assume a pocket formation which readily fits within the toe stiffener and causes the lining to be readily held in place therein. The filler 21 engages over the box toe and the 50 edges of the lining. The lining is then wet and the forepart of the shoe is drawn back over a heated form as shown in Figure 3. This acts to smooth out all the wrinkles in the lining, which is thus ironed to conform 55 smoothly to the upper, and produces an excellent inside surface for the shoe. If a stiffener softened by heat is employed this permits the stiffener to be shaped smoothly and also causes the stiffener to adhere to the adjacent portions of the shoe. The shoe is then 60

taken off the heated form and is allowed to dry thoroughly so that the sole becomes thoroughly fixed in its molded condition. The counter and shank piece are then placed in position and the shoe is then finished as hereinbefore described, a heated counter form being employed if desired. Where previously molded toe stiffeners are employed the shoe is usually of a sufficiently high grade to make 70 relasting for the finishing operations advisable. 75

While as shown the molding of the shoe sole is accomplished by the use of dies, it is evident that it could be performed, but to a less perfect degree, by relasting and pounding out the 80 sole in the usual manner, the last then being removed for the subsequent operations.

Having thus described certain embodiments of this invention it will be evident to those skilled in the art that many changes and 85 modifications might be made therein without departing from its spirit or scope as defined by the appended claims.

I claim:

1. The method of making turn shoes which 90 comprises lasting the shoe wrong side out, removing the last, turning the shoe, molding the sole to finished form and smoothing the toe portion of the shoe over a form, removing the shoe from the form, permitting the 95 shoe to dry, and finishing the shoe.

2. The method of making turn shoes which 100 comprises lasting the shoe wrong side out, removing the last, turning the shoe, molding the sole to finished form and smoothing the heel portion of the shoe over a form, removing the shoe from the form, permitting the 105 shoe to dry, and finishing the shoe.

3. The method of making turn shoes which 110 comprises lasting the shoe wrong side out, removing the last, turning the shoe, molding the sole to finished form and smoothing the heel portion of the shoe over a heated form, removing the shoe from the form, permitting the 115 shoe to dry, and finishing the shoe.

4. The method of making turn shoes which 120 comprises lasting the shoe wrong side out, removing the last, turning the shoe, molding the sole to finished form, smoothing the toe and heel portions over forms, removing the shoe from the forms, permitting the shoe to dry, and finishing the shoe.

5. The method of making turn shoes which 125 comprises lasting the shoe wrong side out, removing the last, turning the shoe, molding the sole to finished form, smoothing the toe and heel portions over forms, removing the shoe from the forms, permitting the shoe to dry, and finishing the shoe off a last.

6. The method of making turn shoes which 130 comprises lasting the shoe wrong side out with a tempered toe stiffener therein, removing the last, turning the shoe, molding the sole to form, drawing the toe portion of the shoe over a form to shape the toe stiffener

and smoothing the outer face thereof, removing the shoe from the form and drying and then finishing the shoe.

7. The method of making turn shoes which comprises lasting the shoe wrong side out with a tempered toe stiffener therein, removing the last, turning the shoe, molding the sole to form, drawing the toe portion of the shoe over a form to shape the toe stiffener and smoothing the face thereof, removing from the form and permitting the shoe to dry, assembling a counter and shank piece in the shoe and tucking the lining, smoothing the outside of the shoe about the counter, and finishing the shoe.

8. The method of making turn shoes which comprises lasting the shoe wrong side out with a tempered toe stiffener therein, removing the last, turning the shoe, molding the sole to form, drawing the toe portion of the shoe over a form to shape the toe stiffener and smoothing the face thereof, removing from the form and permitting the shoe to dry, assembling a counter and shank piece in the shoe and tucking the lining, smoothing the outside of the shoe about the counter, and finishing the shoe off a last.

9. The method of making turn shoes which comprises fixing together opposite edges of a shoe lining at the toe, lasting the shoe wrong side out, stitching the shoe, drawing the last, turning the shoe, molding the sole, inserting a previously molded box toe and tucking the lining therein, wetting the lining at the toe, pulling the toe portion over a heated form to smooth the lining and the forepart of the shoe upper, removing the shoe from the form, permitting the shoe to dry, and then completing the shoe.

10. The method of making turn shoes, 40 which comprises lasting the shoe wrong side out on a last with the sole in temper, pulling the last, turning the shoe, and performing all the subsequent operations, including shaping and finishing the shoe off a last.

11. The method of making turn shoes which comprises lasting the shoe wrong side out on a last with the sole in temper, pulling the last, turning the shoe, and performing all the subsequent steps for completing 50 the shaping of the shoe off a last.

In testimony whereof I have affixed my signature.

MILTON L. DODGE.
